CLAIM

The ornamental design for a tracking device enclosure, as shown and described.

DESCRIPTION

FIG. 1 is a front, left, top perspective view of a tracking device enclosure in accordance with the present invention;

FIG. 2 is a rear, right, top perspective view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a front elevation view thereof; and,

FIG. 8 is a back elevation view thereof.

The broken lines represent portions of the structure that form no part of the claim.

1 Claim, 8 Drawing Sheets
